Attorney.

UNITED STATES PATENT OFFICE.

EDWARD L. PERRY, OF PATERSON, NEW JERSEY, ASSIGNOR TO HIMSELF
AND HENRY S. WINANS, OF LONG ISLAND CITY, NEW YORK.

ROD-PACKING.

SPECIFICATION forming part of Letters Patent No. 339,925, dated April 13, 1886.

Application filed October 30, 1885. Serial No. 181,381. (Model.)

To all whom it may concern:

Be it known that I, EDWARD L. PERRY, a citizen of the United States, residing at Paterson, in the county of Passaic and State of New Jersey, have invented certain new and useful Improvements in Rod-Packings; and I do hereby declare that the following is a full, clear, and exact description of the same, reference being had to the annexed drawings, making a part of this specification, and to the letters and figures of reference marked thereon.

Figure 1 of the drawings is a perspective view of my improved packing, showing the four sections placed together; Fig. 2, similar views in detail of the two horizontal sections of the packing, the two vertical sections, forming each one of the horizontal sections, being shown as together; Fig. 3, detail views of the two vertical sections forming the lower one of the horizontal sections; Fig. 4, a modification of my invention.

The present invention has relation to sectional packing for rods, either steam or water; and the object thereof is to provide a simple and practical packing, as will be hereinafter described and claimed.

In the accompanying drawings, A represents the packing, of suitable material, formed in two longitudinal sections and two vertical sec-

tions, the two longitudinal sections being 30 formed by the two vertical sections B C and D E. The sections B C D E have extensions a to form a clutch-connection when brought together, as shown in Fig. 1, thus breaking the joints and preventing steam from escaping. 35

In Fig. 4 I have shown a modification of my invention, whereby the clutch-connection is dispensed with, and I provide rings b, of duck or fibrous material, to hold the lubricant.

Having now fully described my invention, 40 what I claim as new, and desire to secure by Letters Patent, is—

1. A packing divided horizontally and vertically into four sections, each of which is formed with an extension to form a clutch-connection when the sections are together, substantially as and for the purpose set forth. 45

2. A packing consisting of four sections having rings of duck inserted in the packing, substantially as and for the purpose set forth. 50

In testimony that I claim the above I have hereunto subscribed my name in the presence of two witnesses.

EDWARD L. PERRY.
